UNITED STATES PATENT OFFICE.

ERNST G. K. ANDERSON, OF CHICAGO, ILLINOIS, ASSIGNOR, BY MESNE ASSIGNMENTS,
TO APPLETON ELECTRIC CO., OF CHICAGO, ILLINOIS, A CORPORATION OF ILLINOIS.

ADJUSTABLE SPOTLAMP.

Application filed December 23, 1920. Serial No. 432,663.

To all whom it may concern:

Be it known that I, ERNST G. K. ANDERSON, a citizen of the United States, and a resident of Chicago, in the county of Cook and State of Illinois, have invented certain new and useful Improvements in Adjustable Spotlamps; and I do hereby declare that the following is a full, clear, and exact description thereof, reference being had to the accompanying drawings, and to the characters of reference marked thereon, which form a part of this specification.

This invention relates to improvements in universally controllable spot lamps and refers to a novel spot lamp and mounting therefor which adapts the lamp to closed cars, such as limousines, coupé car bodies, and other bodies with folding tops at times when the top and curtains are up; in short to situations where the lamp casing itself cannot be conveniently reached by the driver of the car or other person within the car to adjust the position of the lamp. To this end the lamp can be supported on a suitable part of the car body, top or like place with the lamp outside the car and with the means for adjustably directing the lamp in position for convenient access, as within a closed car. When the spot lamp is of that type having an extension conductor cord, the normal support for the cord can, if desired, be made part of the lamp mounting and carried by a bracket structure that also carries the lamp. The improvements are herein shown as adapted to the latter form of extension spot lamp, although not limited thereto.

Among the objects of the invention is to provide a simple and effective spot lamp which can be so mounted on the car as to permit of all the usual movements of the spot light by operating means that are contained within the closed car body so that the lamp can be adjusted to all positions from within the car body.

A further object of the invention is to provide a novel mounting and actuating device for a spot lamp of this character.

Other objects of the invention are to improve and simplify adjustable spot lamps, and the invention consists in the combination and arrangement of the parts shown in the drawings and described in the specifica-

tion, and is pointed out in the appended claims.

In the drawings:

Figure 1 is a perspective view of a portion of the inner side of a closed car body, showing the manner of applying my improved spot lamp thereto.

Figure 2 is a sectional view of the mounting and the operating means for the lamp, showing the wall or supporting member of the car body in section.

Figures 3 and 4 are details of the swing lamp mounting, showing the lamp in different positions.

Figure 5 is a plan view of the lamp mounting, with the supporting part on the car body in section.

Figure 6 is a fragmentary view of the lamp adjusting means.

Figure 7 is a fragmentary view illustrating the lamp support and actuating means as seen from the inner side of the car.

Figure 8 is a section on the line 8—8 of Figure 2.

As shown in the drawings, my improved lamp and mounting is supported on the frame member 10 of the door 11 of a closed car adjacent to the fixed and tiltable wind shields 12 and 13, respectively. It will be understood, however, that so far as the location of the lamp and its mounting is concerned, such location may be otherwise selected. This location, however, is convenient to the driver.

The section of the door frame 10 is shown in Figures 2 and 5. The active elements of the lamp itself are exterior to the support 10, while the means for actuating the movable parts of the lamp so as to variously direct its rays are located within the car body and just inside the support or wall member 10.

The mounting for the lamp, as herein shown, is made as follows:

14 designates a horizontal tube member which extends through and is adapted to rotatively fit at its inner end in a bearing 100 in the frame or support 10. The tube terminates a short distance inside the support 10, and a weather-proof joint can be formed around the tube at its inner end by means of a preferably friction washer 15 that is 105 axially pierced to receive the tube and is

seated flat against the inner side of the support 10 and can be pressed against the flat, inner face of said support by bracket member 16, forming a clamping plate which 5 is axially and nonrotatively seated in a groove 17 of said tube. In practice the inner end of the tube is reduced in diameter and the opening of the bracket member 16 is of a diameter to fit tightly thereon and, 10 when fitted thereto the tube member may be upset or swaged over said member 16 to constitute a head 17', which forcibly presses the resilient or joint-making member 15 against the mounting support. This bracket 15 member 16 is formed to provide bracket arms 18 for a purpose hereinafter to be described.

Extending through and fitting closely in said tube 14 is a tubular shaft 20. It extends a distance outwardly beyond the tube to constitute a lamp operating terminal 21. It also extends inwardly beyond the tube and inside the car body and thereat has a flattened formation 22, as herein shown, on 25 which is mounted a switch 23 hereinafter to be more particularly referred to. The shaft 20 is hollow to afford a conduit or passage 24 for the lamp conductor cord 25, one branch c^1 of which is adapted for connection to a battery or other source of current supply, and the other branch c^1 of which is divided and includes switch contacts c^2 , c^3 that are adapted to be bridged by a suitable switch c^4 , the mounting of which 30 is designated as a whole by 23; the conductor c^5 beyond the contacts going back to the battery or other source of current supply.

The outer end of the tube 14 is externally threaded at 28 to engage an internally 40 threaded sleeve nut 29, whose function is to directly support the lamp structure in the arrangement herein shown, and as herein-after will be described. As herein shown, the tube 14 extends through a cone-like 45 block 31 fitted against the outer face of the support or wall member 10 around the bearing therein through which the tube emerges. This block is fastened to said support or wall member 10 by means of screws 31'. A water proof joint can be made between the outer smaller end of the block and tube 14 by a nut 32 threaded to the tube 14, a lock nut 33 bearing thereagainst and a compressible packing 34 between the nut 32 and the 50 bottom of a recess 35 in the smaller end of said block which receives said nuts and packing. The clamping action and reaction of said nuts has the effect to press the friction washer 15 and the compressible packing 55 against their seats on the wall member and block, respectively. The use of the block 31 avoids the necessity of marring the wall member or door frame to adapt the structure, when employed in connection with the 60 wall member of a closed car body.

The outer end of the threaded sleeve nut constitutes a direct support for the lamp structure which is designated as a whole by 36. The sleeve nut 29 is locked on the tube 14 by a nut 29' threaded to the tube 14 and backed by a lock nut 29''. The connection between the sleeve nut and lamp structure, as herein shown, comprises a bracket 37 that is fixed to or made integral with a neck portion 38 of a shell, designated as a whole by 39, to contain the rewinding reel for the extension conductor cord, when an extension cord is employed. The connection between the bracket 37 and the sleeve nut 29 is afforded by reducing said sleeve nut and 75 piercing the bracket 37 to pass thereover, and thereafter upsetting the end of the sleeve nut to constitute a holding shoulder 40 which non-rotatively fixes the lamp structure to said nut. The bore of the outer end 80 of the sleeve nut is reduced to form a bearing for the tubular shaft 20 closely adjacent to the swivel connection of the tubular shaft 20 to the block 54.

Referring to Figure 6, it will be noted 90 that the neck portion of the reel casing has an externally threaded terminal 41 fitted over by an internally threaded and externally knurled nut 42. The upper end of said nut is partially closed to constitute a downwardly facing shoulder 43.

45 designates, as a whole, the body or casing of the lamp that is provided with a hollow curved neck portion 46 through which the conductor cord 25 extends on its way 100 from the reel to the switch. Said hollow neck is provided with a downturned end that has an external cone formation 48 which fits an internal seat 49 that is formed in the upstanding terminal 41. The said 105 cone-like parts are forced together by engagement of the shoulder 43 on the nut 42 against an upwardly facing annular shoulder 51 on the neck portion 46. The engagement of the tapered portions is such that the 110 nut 42 will lock the tapered parts from relative turning due to vibration, but will permit them to relatively turn when a permissible manual force is applied to the lamp.

Such manual force is applied to the lamp 115 through the horizontal portion of the neck 46 by the following means:

To the terminal 21 of the tubular shaft 20 is fixed, as by means of a set screw 53, a block 54. Said block is provided at its upper edge with a slot 55 downwardly into which projects a lug 56 that is fixed to and depends from the horizontal portion of the lamp supporting neck 46.

With this construction it will be observed 125 that when the tubular shaft 20 is axially moved, it carries the block 54 with it and, by reason of the swivel connection between said block and the lamp supporting neck 46 afforded by the slot 55 and lug 56, the said 130

lamp casing will be swung or rocked about the axis of the downturned end of the neck 46, as permitted by the sufficiently loose fit between the engaging cone-like parts of said neck and the taper on the reel casing or shell. Therefore, when the said shaft 20 is forced in one direction, the lamp casing will be turned in a horizontal plane in one direction, and when the shaft is moved in the other direction the lamp casing will be horizontally turned in the other direction. This gives a range of horizontal adjustment for the lamp casing and the lamp supported thereby.

15 Such axial movement of the hollow shaft 20 is controlled from the driver's station inside the car body by means made as follows:

That portion of the shaft 20 which lies 20 inside the car body is flattened to produce the inner terminal 22 above referred to, and said flattened portion carries at its inner end and on both sides anti-friction rollers 58 which travel in a track 59 of a hand lever 60 that is pivoted by a pivot pin 61 to the bracket arms 18 of the frame member 16 before referred to. The track portion 59 referred to is formed by making the hand lever 60 hollow and giving it a formation 25 that produces between its pivot and manually directed end a rather sharp angle portion 63. The inner side of the hand actuated cam lever is slotted or open at 64, as shown in Figures 2 and 8, to permit the inner terminal 22 of the shaft 20 to pass therethrough; and the anti-friction rollers 58, which are rotatively mounted on the end of the flattened terminal are placed within the hollow or channel shaped hand lever 40 through one of its open ends during the assembling operation.

With this construction it will be noted that when the lower end of the hand lever is pulled inwardly or away from the support 10, it serves to move the shaft 20 towards the closed car body, and through the swivel connection, due to the slotted block 54 and the lug 56, the lamp casing will be swung in a horizontal plane inwardly towards the car, as shown in Figure 4. When the hand lever is swung in the other direction, the opposite adjustment of the lamp casing and its lamp will be effected, as will be clear from an inspection of Figure 3. 55 In Figure 4, it can be assumed that the parts are in position to effect the greatest throw of adjustment of the lamp casing away from the closed car body. In Figure 5 the adjustment corresponds to that shown in Figure 1, wherein the lamp casing is adjusted directly forward. Figure 3 indicates innermost adjustment of the lamp structure.

60 The lamp structure may be adjusted in a vertical plane by turning the tubular support 14, which may be effected by grasping

the lever 60 and bracket 16 in much the same manner as grasping a door knob, and turning it either forwardly or rearwardly, and thereby effect angular adjustments of the lamp structure in a vertical plane. 70

With these two positive adjustments, it will be observed that numerous combinations thereof will effect a substantially universal adjustment of the lamp structure about the axis of the nut 42 and the axis 75 of the shaft 20, so that light may be projected from the lamp in all directions and by means which are readily accessible inside a closed car body.

It will be understood that the structural 80 details illustrated may be varied within the spirit and scope of the claims hereto appended and that the invention is not limited to the details of construction shown, except as to claims wherein the details are specifically 85 set forth, and as imposed by the prior art.

I claim as my invention:

1. An adjustable lamp mounting, comprising a horizontal, hollow, rocking lamp support adapted to extend through and be 90 supported by a wall member and extending inwardly and outwardly therebeyond, clamping means operative endwise of said support to fix said support to the wall and to provide weather-proof joints between it and both sides of said wall including a clamping plate fixed to the inner end of said support inside said wall member, threaded means exterior to the wall member, engaging said hollow, rocking support to exert endwise clamping stress on said support, packing elements between said inner and outer members and said wall, a lamp mount carried by the outer end of said support and swinging and rocking actuating 100 means attached to the inner end of said support. 105

2. An adjustable lamp mounting, embracing a horizontal, hollow, rocking support adapted to extend through and be supported by a wall member and extending inwardly and outwardly therebeyond, clamping means operative endwise of said support to fix said support to the wall and to provide weather-proof joints between it and both sides said wall, including a clamping plate fixed to the inner end of said support inside said wall member, said clamping means including threaded means engaging said support exterior to the wall member, on said hollow, rocking support to exert endwise clamping stress on said support, packing elements between said inner and outer members and said wall, a lamp structure mounted on the outer end of said support by means permitting vertical and horizontal adjustment of the lamp structure, and lamp adjusting means including means to rock said support, and a member which extends through and has bearing in and is axially 110 115 120 125 130

displaceable along said hollow support and provided inwardly beyond said wall with swinging means to axially displace said member.

5. 3. An adjustable lamp mounting, comprising a hollow rocking support adapted to extend through and be supported by a wall member and to extend inwardly and outwardly therebeyond, a lamp mount provided on the outer end of said support for horizontal turning adjustment therewith, including an angular fitting, one arm of which is a pivotal member rotatable about its long axis and the other arm of which is a lamp supporting member, axially displaceable means extending through the support and operatively connected at one end to said lamp mount by means to swing the latter horizontally, and manually operable swinging and rocking means at the inner end of the support to rock and give endwise movement to the support and axially displaceable means, respectively.

4. The combination with a wall member 25 of a controlling member for a universal lamp mount, including a rocking supporting tube which extends through and has a rotative bearing in said wall member, a lamp mount fitting carried by the outer end 30 of said tube, an endwise displaceable control member loosely connected at its outer end to said mount and extending inwardly through the tube, a rocking and swinging hand piece for connection to said tube and 35 said controlling member, a packing plate fixed to the inner end of said tube to the forced towards the inner side of said wall member, and a nut threaded to said tube exterior to said wall member and acting 40 through its screw-threaded connection to said tube to force the nut and the packing plate toward each other and against packing members on the opposite sides of said wall.

45. 5. An adjustable lamp mounting embracing a lamp mount including a frictionally restrained L-shaped lamp supporting fitting, one arm of which is adapted to carry said lamp, a rocking, frictionally restrained 50 support adapted to extend through and be supported by a wall member, the other arm of said fitting being pivotally carried by a fixed part on the outer end of said rocking support so as to be rotatable about the 55 long axis of said arm, axially displaceable means extending through said rocking support and operatively connected at its outer end to the lamp carrying end of said fitting, and manually operable rocking and endwise 60 displacing means at the inner end of the rocking support to turn the latter and to give endwise movement to the axially displaceable means, respectively.

65. 6. The combination with a wall member and a controlling member for a universal

lamp mount, comprising a tube extending through and having rotative bearing in said wall member, a support for a universal adjustable lamp structure arranged on the outer end of said tube, an angular member 70 having one arm connected to said support so as to be rotatable around the long axis of said arm, means for supporting a lamp on the other arm of said angular member, a swinging and rocking hand piece on said tube inwardly beyond said wall, and a second controlling member loosely connected to said angular member and extending inwardly through said tube and operatively connected to said hand piece, whereby said 75 tube can be turned about its long axis and said second controlling member can be axially displaced.

7. An adjustable lamp mounting, embracing a bracket member having a conical seat, 80 an angle lamp supporting fitting having on one arm a tapered part to engage said seat, with means to hold them frictionally together, a hollow, rocking support adapted to extend through and to be sustained by 85 and frictionally locked to a wall member and rigidly fixed at its outer end to said fitting, an axially displaceable member extending through and guided by said support and having a swiveling connection at its 90 outer end with the said fitting, and means to rock said support and to axially displace 95 said member.

8. An adjustable lamp mounting, embracing a horizontal hollow, rocking support 100 adapted to extend through and be supported by a wall member to rotate therein and provided at its outer end with means to fixedly support a lamp to permit it to swing in one plane, an endwise displaceable member extending through and having bearing principally throughout its length in said hollow support, a swiveling connection between the outer end of said member and a crank portion of a rocking lamp support, a bracket 105 non-rotatively fixed to the inner end of said hollow support and bearing against said wall, and a lever hinged to said bracket and connected to the inner end of said endwise displaceable member.

9. An adjustable lamp mounting, embracing a horizontal hollow, rocking support adapted to extend through and be supported by a wall member to rotate therein and provided at its outer end with means to support a lamp to permit it to swing in one plane, and an endwise displaceable member extending through and having bearing in said hollow support, a swiveling connection between the outer end of said member and the crank portion of a rocking lamp support, a bracket non-rotatively fixed to the inner end of said hollow support and bearing against said wall, a lever hinged to said bracket and provided with a longitudinal 125 130

- track having angularly disposed parts, and a bearing roller on the inner end of said endwise displaceable member engaging said track.
- 5 10. An adjustable spot lamp for closed car bodies comprising a tubular support for the lamp structure adapted to extend through, and at both sides beyond, and to be rotatively supported by a wall member of a 10 car body, a bracket fixed on the outer end of said support, an L-shaped fitting, one arm of which has rocking bearing in said bracket to permit it to swing about its long axis, an axially displaceable member supported by and having bearing in said hollow support, and swiveling means to connect said axially displaceable member to the other arm of said fitting.
11. An adjustable lamp mounting, comprising a tubular support adapted to extend through and at both ends beyond, and to be rotatively supported by a wall member, a lamp structure supported on the outer end of the tubular 25 member exterior to said wall member and frictionally restrained but capable of horizontal and vertical adjustments, an endwise movable and rocking shaft extending through and beyond and having bearing in 30 said tubular support and operatively connected at its outer end to the lamp structure, a bracket at the inner side of said wall member fixed to said tubular member to rotate the same, a lever pivoted to the bracket 35 and connected to said shaft to give endwise movement thereto, packing surrounding said tubular support interior and exterior of said wall member, and means to exert pressure on said packing to afford weather- 40 proof joints between said tubular support and said wall member.
12. An adjustable spot lamp for closed car bodies, embracing a tubular support adapted to extend through and be rotatively supported by a wall member, said tubular support being exteriorly threaded at its outer end, an elongated tubular nut engaging said threaded portion of the support, with means to lock it thereon, a lamp structure capable 45 of vertical and horizontal adjustment and fixed directly to said nut, permitting said structure to be swung vertically when said tubular support is rotated, a shaft extending through and axially movable in said 50 tubular support, means for loosely connecting the outer end of said shaft to the lamp structure to swing it horizontally, and means adapted to the inner side of the wall member for imparting rocking and axial 55 movements to said tubular member and shaft, respectively.
13. An adjustable spot lamp for closed car bodies, embracing a tubular support adapted to extend through and be rotatively supported by a wall member, said tubular support being exteriorly threaded at its outer end, an elongated tubular nut engaging said threaded portion of the support, with means to lock it thereon, a lamp structure capable 60 of vertical and horizontal adjustment and fixed directly to said nut, permitting said structure to be swung vertically when said tubular support is rotated, a shaft extending through and axially movable in said tubular support, means for loosely connecting the outer end of said shaft to the lamp structure to swing it horizontally, means adapted to the inner side of the wall member for imparting rocking and axial movements to said tubular member and shaft, respectively, a 65 bracket adapted to the inner side of the wall member and fixed to and rotative with said tubular support, and a lever hinged on said bracket and connected to said shaft to give endwise movement thereto.
14. An adjustable spot lamp for the purpose set forth comprising a tubular member adapted to extend through and be rotatively supported by a fixed member, a shaft axially movable in said tubular member, a tubular 70 nut threaded to said tubular member, a lamp structure fixed to said tubular member to swing therewith in one direction, and embracing a part having a tapered socket at an angle to said tubular member, an L-shaped fitting having a cone-like part to engage said tapered socket, with means to force the tapers together to frictionally lock them, and a swivel connection between said axially movable shaft and said fitting.
15. An adjustable spot lamp for the purpose set forth comprising a tubular member adapted to extend through and be rotatively supported by a fixed member, a shaft axially movable in said tubular member, a tubular nut threaded to said tubular member, a lamp structure fixed to said tubular member to swing therewith in one direction, and embracing a part having a tapered socket at an angle to said tubular member, an L-shaped fitting having a cone-like part to engage said tapered socket, with means to force the tapers together to frictionally lock them, a member fixed to the outer terminal end of said shaft and provided with a slot at right angles to said shaft, and a pin extending from said bracket into said slot.
- In witness whereof I claim the foregoing as my invention, I hereunto append my signature this 11 day of December, 1920.
- ERNST G. K. ANDERSON.
